United States Patent Office

Des. 232,249
Patented July 30, 1974

232,249

PLAYGROUND CLIMBER

Nancy Reed Markusen, Grand Forks, N. Dak., assignor
to University of Idaho Research Foundation, Moscow,
Idaho

Filed May 30, 1972, Ser. No. 258,220

Term of patent 14 years

Int. Cl. D21—01
U.S. Cl. D34—5 H

FIG 1

FIG 2

FIG 3

FIG 4

FIG. 1 is a perspective view of a playground climber showing my new design;

FIG. 2 is a side elevational view;

FIG. 3 is an end elevational view; and

FIG. 4 is a top plan view, the bottom of the unit being plain and unornamented.

I claim:

The ornamental design for a playground climber, as shown and described.
